CLAIM

The ornamental design for a kettle lid handle, as shown and described.

DESCRIPTION

FIG. 1 is a top, front, right side, perspective view of a kettle lid handle;

FIG. 2 is a front elevation view thereof, the device being rotationally symmetric;

FIG. 3 is a top plan view thereof;

FIG. 4 is a bottom plan view thereof; and,

FIG. 5 is a top, front, right side, perspective view thereof, shown with environment.

In the drawings, the broken lines are for the purpose of illustrating environment only and form no part of the claimed design.

1 Claim, 2 Drawing Sheets
